SEARCHED
UNITED STATES PATENT OFFICE.

THOMAS EARL DE VOL, OF BELGRADE, NEBRASKA.

AUTOMATIC DUMP-LOCK.

Specification of Letters Patent.

Patented May 25, 1920.

1,341,499.

Application filed November 13, 1918. Serial No. 262,409.

To all whom it may concern:

Be it known that I, THOMAS EARL DE VOL, a citizen of the United States, residing at Belgrade, in the county of Nance and State 5 of Nebraska, have invented certain new and useful Improvements in an Automatic Dump-Lock, of which the following is a specification.

This invention relates to an improved 10 dump lock for use in connection with a dumping platform upon which vehicles will be unloaded and the principal object of the invention is to so construct this lock that it may be used in connection with a conventional construction of dump and the 15 dumping or tilting platform securely held against being accidentally released and moving to a dumping position. Another object of the invention is to so construct this lock 20 that it may be associated with the trap door covering the hopper of a bin, opening of the trap door moving the lock to an inoperative position and closing of the trap door moving the lock to an operative position. Another object of the invention is to 25 so construct this lock that it will be simple in construction and strong and durable and comprise a comparatively small number of parts. This invention is illustrated in the 30 accompanying drawings wherein—

Figure 1 is a top plan view of a dumping platform of a conventional construction having the lock associated therewith,

Fig. 2 is a longitudinal sectional view 35 through the structure shown in Fig. 1,

Fig. 3 is a view similar to Fig. 2 with the trap door open and the dumping platform in a tilted position,

Fig. 4 is a transverse sectional view taken 40 along the line 4—4 of Fig. 1,

Fig. 5 is a sectional view taken along the line 5—5 of Fig. 1,

Fig. 6 is a fragmentary perspective view 45 showing the manner in which the locking bars engage the supporting arms of the tilting platform.

This dumping platform is of a conventional construction and will be mounted in the flooring 10 of a mill and will consist 50 of the usual tilting beams 11 pivotally mounted upon the axle 12 for swinging movement from the position shown in Fig. 2 to that shown in Fig. 3.

In order to support the beams 11 in a horizontal position there has been provided a 55

rocker bar 14 which is mounted in enlarged socket openings 15 formed in the standards constituting keepers 16, the socket openings 15 being sufficiently large to permit free rotary movement of the rocker bar 14. This 60 rocker bar 14 carries supporting arms serving as latches 17 which extend upwardly, and from an inspection of Figs. 2 and 3 it will be seen that when this rocker bar is moved through the medium of the lever arm 65 18 and handle 19 the standards or keepers may be moved into and out of engagement with the beams, it will thus be seen that after a wagon has been placed upon the platform the supports may be swung to the inoperative 70 position and the grain or other material in the wagon dumped into the bin to one side of the partition 20 and the platform then returned to the horizontal position and secured after which the vehicle 75 can be removed. The structure as far as described is a conventional form of tilting platform and supports for holding the same in a horizontal position. It has been found that in use the supports for the tilting platform will accidentally move to a releasing 80 position thus releasing the platform and often causing injury to animals as well as people working about the mill and it is to overcome this objection and provide means 85 for securely locking the supports in an operative position that the improved lock now to be described has been developed.

The locking structure for the platform supports is mounted beneath the flooring 90 and is provided with a rocker shaft 21 having arms 22 extending from its outer end portions and an intermediate arm 23 with which the draw bar or actuating bar for the locking structure will be connected. The 95 draw bar 24 extends through a slot 25 in the flooring 10 and is connected with the trap door through the medium of the bearings 26. It will be readily seen that when the trap door is grasped by the handle 27 100 and swung upwardly the rocker shaft will be rotated to swing the arms 22 in a direction away from the partition 20 and further that when the door 13 is closed the rocker shaft will be rotated to swing these arms 105 22 toward the partition. Links 28 are pivotally connected with the arms 22 and extend forwardly toward the partition 20 upon opposite sides of the inlet 29 closed by the trap door and have their forward ends rig- 110

idly connected with the locking bars 30 which pass through the partition into position for engagement with the supporting arms 17 when the trap door is closed. It 5 will thus be seen that after the platform has been returned to the horizontal position and the trap door closed, the closing of this trap door will move the locking structure to bring the locking arms into engagement 10 with the supporting arms and thus securely hold the supporting arms against movement to a releasing position until the trap door has been again opened. This trap door would not be opened until ready for use and 15 therefore there would be no danger of the tilting platform becoming released and swinging to the tilted position accidentally. There has thus been provided a locking structure for the platform support which 20 will be very efficient in operation and which

will move into and out of an operative position as the trap door is closed or opened.

Claim:

The combination with a bin having a vertically swinging closure at its top, of a supported tilting platform arranged at one side of the bin adjacent to the closure and normally in the same plane therewith, keepers arranged on the bin, a rocker in the keepers, arms on the rocker and forming latches en- 25 gageable with the platform to hold it against tilting movement, manually controlled means for actuating the rocker to bring the same to releasing position, and means connected with the closure and active 30 upon the latches to hold the same on move- 35 ment of the closure in one direction.

In testimony whereof I affix my signature hereto.

THOMAS EARL DE VOL.
